UNITED STATES PATENT OFFICE

91,977

DESIGN FOR A REPRODUCTION PRINTING MACHINE OF THE VACUUM TYPE

Michael Annick, Scranton, Pa., assignor to F.
Wesel Manufacturing Company, Scranton, Pa.

Application January 15, 1934, Serial No. 50,404

Term of patent 14 years

To all whom it may concern:

Be it known that I, MICHAEL ANNICK, a citizen of the United States, residing at 617 Harrison Avenue, in the city of Scranton, county of Lackawanna, State of Pennsylvania, have invented a new, original, and ornamental Design for Reproduction Printing Machine of the Vacuum Type, of which the following is a specification, reference being had to the accompanying drawing, forming part thereof.

The figure is a perspective view of a reproduction printing machine of the vacuum type, showing my new design.

I claim:

The ornamental design for a reproduction printing machine of the vacuum type, as shown.

MICHAEL ANNICK.
